CLAIM

The ornamental design for a lower body physical exerciser, as shown and described.

DESCRIPTION

FIG. 1 is a side elevational view of a lower body physical exerciser showing my new design;

FIG. 2 is a front elevational view thereof, the side opposite being substantially identical;

FIG. 3 is a top plan view thereof;

FIG. 4 is a bottom plan view thereof; and,

FIG. 5 is a front perspective view thereof.

FIG. 1

FIG. 2

FIG. 3

FIG. 4

FIG. 5
